METHOD OF MAKING LAMINATED CORES
FOR TRANSFORMERSHerbert E. White, Cleveland Heights, Ohio, and
William H. Borst, Hollis, N. Y.

Application May 6, 1943, Serial No. 485,942

8 Claims. (Cl. 29—155.5)

Our invention relates to transformers and the method of making them, and more particularly to transformer cores and the method of making and assembling them with coils to form transformers.

Heretofore in the manufacture of transformers one practice has been to assemble a plurality of stamped laminations into a core having a closed magnetic path, and to wind coils around portions of this closed path to make a transformer. This requires threading each of the numerous turns of the coils through the center opening in the core, and does not readily lend itself to rapid production of transformers. Another method has been to stamp the core laminations in variously shaped sections, then to slip the legs through a pre-formed coil, and assemble the sections into substantially a continuous magnetic path. For best results with this type of transformer the legs of the shaped sections should be interlaced. This method also does not lend itself to rapid production. Many other methods have been tried but each has one or more time consuming operations which materially increases the cost of production.

It is an object of our invention to provide a means and method for rapid production of good transformers.

An object of our invention is to provide a new method for making a core for a transformer.

Another object of our invention is to provide a new method of assembling a core to form a transformer.

It is an object of our invention to provide a new method of assembling a transformer.

A further object of our invention is to provide a new and improved core for a transformer which facilitates assembly and makes possible rapid mass production of cheap but good transformers.

Other objects and a fuller understanding of our invention will be had by referring to the following specification, taken in conjunction with the drawing in which:

Figures 1 to 6 show steps in the process of making our new core and assembling it into a transformer;

Figure 1 shows as a first step the start of winding a strip of magnetic material around a mandrel.

Figure 2 shows the second step which is the completion of winding the strip a plurality of times about the mandrel.

Figure 3 shows the third step of welding together the successive convolutions of the magnetic material.

Figure 4 shows the wound and welded core after it has been cut into two pieces.

Figure 5 shows the core after the coils have been put in place and the two pieces of core connected together.

Figure 6 is a side view of Figure 5.

Figure 7 shows another form of our invention, and

Figure 8 shows still another form of our invention.

Preferred forms of our invention are shown in the drawing, although it is to be understood that other forms, which will be easily obtained after reading a detailed description of the invention, are considered by us as coming within the scope of our invention.

15 In Figure 1 we show a mandrel 10 which has a slot 11 extending along one side thereof. Positioned in the slot is one end 9 of a long strip of magnetic material 12 which is suitable for making transformer cores. A convenient material thickness for some transformers is one the order of .020 inch thick. The magnetic strip material may be oxidized, or it may have a layer of lacquer or other insulating material on it. After the end of the strip 12 is placed in the slot, the material is 20 bent and several complete turns of the material 12 about the mandrel are made. Tension is maintained on the strip material 12 in order to assure that the successive convolutions will be tight against the previous ones.

25 30 We speak of taking turns of the strip material about the mandrel, but it is to be understood that this is only by way of example, and that on a mass production basis it probably will be much quicker and more satisfactory to mount the mandrel 12 on a shaft 13, and to rotate the shaft. The strip material 12 can be fed from a reel (not shown) and suitable tensioning means can be provided to assure a suitably compact core. Due to the oxide, lacquer, or other insulating material which is on 35 the magnetic strip 12, there will be a thin layer of 40 insulation between the successive convolutions.

45 Figure 2 illustrates the core after the desired thickness has been obtained by making numerous turns of the strip material 12 about the mandrel 10.

50 While tension is maintained on the loose end of the strip material 12, and before the mandrel is removed from the shaft 13, the successive convolutions are fixed together to prevent them from slipping with respect to each other, particular care being exercised to connect the outermost convolution to the one which is underneath it. We prefer to weld across the edges of the convolutions at four places 15, 16, 17, and 18, as is shown 55 in Figure 3.

55 After the four welds have been made, there-

by securing each convolution to its next adjacent convolution, or convolutions, at four spaced points, we cut the core and the mandrel 10 each into two pieces along a line extending between these welds, thereby establishing a first core portion 20 and a second core portion 21. The welds 15 and 17 are preferably adjacent the cut ends of the core portion 20 and prevent the convolutions from slipping with respect to each other. The welds 16 and 18 are adjacent the cut ends of the core portion 21 and prevent the convolutions from slipping with respect to each other. Each portion of the core thereby retains its shape. It is for this reason that we apply the four welds 15, 16, 17, and 18 to the uncut core, and space them in pairs with welds 15 and 16 and welds 17 and 18 being just far enough apart that a saw or other cutting device can pass between them.

After the core and the mandrel have been severed, each into two pieces, the mandrel can be removed from inside the core portions 20 and 21, and the end 9 of the strip material which was inserted into the slot 11 can be straightened out or broken off. We prefer to break it off as it is not necessary to the operation of our device, and this operation is faster than trying to straighten it. Obviously, other holding means which do not leave this bent end to be disposed of may be used. It is also possible to saw through the magnetic material at two places without cutting the mandrel 10 in two, thereby saving it for further use.

It is also possible to slide it sideways out of the core after the core convolutions have been connected together and prior to cutting the magnetic material.

Previously formed primary and secondary coils 23 and 24 comprised of many turns of fine wire may then be slipped onto the legs of one of the core portions, for instance, portion 20. Insulating means 14 may be placed between the core and the coils. We prefer to cut the core near one of the ends as shown, thereby making one end portion 20 substantially larger than the other end portion 21; then the coils 23, 24 are positioned on the larger end portion. After the coils have been slipped into position the cut ends are brought together and held under a slight amount of compression, such as in a vice, and means are provided for connecting the two end portions 20 and 21 together.

Figure 5 illustrates two such means. We prefer to weld the two portions together, such as is shown at points 25. It is also possible to have the welds 25 extend the full height of the core. It is also possible to weld the two portions together by a weld extending between welds 17 and 18. It is also possible to bolt the two portions together, such as is shown at 26. A slight air gap 27 may result but this may be advantageous in some types of transformers, such as arc welding transformers, and the size of the gap may be controlled by inserting a magnetic non-conductor of desired thickness between the ends of the core portions before they are connected together. If the two core end portions 20, 21 do not align exactly, due to the removal of portion 9 of the magnetic material, slight pressure may be applied laterally to force them into alignment. However, due to the thinness of the strip magnetic material 12, this mis-alignment is not serious, and may be overlooked entirely.

We have shown welds 15, 16, 17, 18 only on the top surface of the convolutions of core ma-

terial because if there were a weld across the bottom edges of the convolutions as well as across the top edges there would be established an undesirable magnetic short circuit around the laminations.

Figure 7 illustrates another form of our invention in which the two spaced welds 15 and 16 were replaced by a single weld 30, and the two spaced welds 17 and 18 were replaced by a single weld 31. The core was then cut into the two core portions 20, 21 by sawing along a line 32 extending through the welds 30, 31. In Figure 7 the two resulting portions are shown moved apart. Due to the width of the welds 30, 31 being greater than the width of the saw cut, each cut end of each core portion 20, 21 will have a welded portion which will prevent the convolutions from slipping. Either before or after cutting, the mandrel can be removed. This method may be preferable to the previously described method as it probably will take less time to make one fairly wide weld than it will take to make two spaced welds.

The space between the left edge of weld 15 (Fig. 3) and the right edge of weld 18, and the area of the weld 30 (Fig. 7) may be termed the "weld area" and the core should be cut in two through a "weld area" on each side of the core because each of the two horseshoe-shaped core portions remaining after the cut will then have a welded portion which keeps the laminations of the core portion together. While it is preferable that the "weld area" not extend over a great length of the circumference of the core it is possible that the welds, such as welds 15, 16, be separated by considerable distance so long as the welds defining the spread apart "weld area" enclose only the straight legs of the core. Thus when the core is cut into two portions there is no tendency or opportunity for the laminations to spread apart.

Figure 7 further illustrates how the core portion 20 is wound with a coil, in case a pre-formed coil is not used. The core portion is mounted in two caps, 34, and 35, which are designed to hold the two cut ends of the core portion. From each cap 34, 35 there is a bent arm 36, 37; the arm 37 terminating in a fixed bearing 38, and the arm 36 being mounted in a bearing 40 and being connected to a motor 39 which is adapted to rotate the arm 36 thereby rotating the core 20 and the arm 37. The arms 36, 37 are bent in a direction such, and are just long enough, that the axis of rotation of the system extending through the bearings 38, 40 passes through substantially the center of the core portion 20. A reel 41 supplies wire 42 which is wound about the core portion 20 to form a coil 43.

Figure 8 illustrates another form of invention in which the convolutions are held together by bolts and nuts 33 instead of by welding.

The mandrel 10 about which the magnetic strip material is wound can be any shape, such as round, oval, square, oblong, etc.; and may be made of any material. We prefer to use wood as it is inexpensive and easy to saw through.

Although we have described our invention with a certain degree of particularity, it is to be understood that it is only by way of example and that numerous changes in the details of construction and the combination and arrangement of parts may be resorted to without departing from the spirit and the scope of the invention as hereinafter claimed.

We claim as our invention:

1. The method of making a transformer comprised of a core and coil means about said core, which comprises the steps of: spirally winding a length of flat magnetic material to establish a core having a plurality of convolutions and forming a closed magnetic path, welding each of said convolutions to its next adjacent convolution to establish a plurality of welded areas across one edge face only of said core, cutting said core at a plurality of places each of which is between the outer ends of one of said welded areas to establish core portions, applying coil means to at least one of the core portions, and connecting the cut ends of said core portions together to re-form substantially a closed magnetic path.

2. The method of making a transformer comprised of a core and coil means about said core, which comprises the steps of: spirally winding a length of flat magnetic material to establish a core having a plurality of convolutions and forming a closed magnetic path, welding said convolutions together in a direction across said convolutions, cutting through said core and through said weld to establish two separate core portions, the width of said weld being sufficiently greater than the width of the cut that each core portion includes an end portion having a portion of the weld whereby the positions of the severed convolutions with respect to each other in each of said separate core portions is maintained, applying coil means about at least one of said two core portions, and then connecting said two core portions together to reform substantially the original core.

3. The method of making a transformer comprised of a core and coil means about said core, which comprises the steps of: spirally winding a length of flat magnetic material to establish a closed magnetic path core having a plurality of convolutions and having two rounded portions with straight side portions therebetween, welding said convolutions together in a direction across said convolutions and substantially at one of the junctions between a curved portion and the straight side portions, cutting through said weld to establish two separate dis-similar core portions one of which includes substantially all of said straight side portions, the width of said weld being sufficiently greater than the width of said cut that each of said core portions includes an end portion having a portion of the weld whereby the positions of the severed convolutions with respect to each other in each of said separate core portions is maintained, applying coil means to the said core portion which

includes said straight side portions, and then connecting said two core portions together to reform substantially the original core.

4. The method of making a transformer comprised of a core and coil means about said core, which comprises the steps of providing a length of flat magnetic core material, spirally winding said flat core material to establish a core having a number of convolutions which define a closed magnetic path, applying a plurality of weld means across the convolutions on only one end face of the said core for connecting the said convolutions together, cutting through said core and through said weld means thereby severing said core into at least two portions each having weld means adjacent its severed ends, applying coil means to at least one portion of said core means, and connecting said at least two core portions together by welding over and along the said welds which are adjacent the said severed ends.

5. The method as set forth in claim 1 further characterized in this: that said cut ends of the core portions are connected together by welding to reform substantially a closed magnetic path.

6. The method as set forth in claim 2 further characterized in this: that said two core portions are connected together by welding to reform substantially the original core.

7. The method as set forth in claim 3 further characterized in this: that said two core portions are connected together by welding to reform substantially the original core.

8. In the method of making a transformer comprised of a core and coil means about said core, which comprises the steps of: spirally winding a length of flat magnetic material to establish a core having a plurality of convolutions and forming a closed magnetic path, connecting each of the said convolutions to its next adjacent convolution by welding across said convolutions at two pairs of places on one edge face only of said core, one pair of said welds being on one leg of said core and the other pair of said welds being on the other leg directly across the core therefrom, and said welds in each of said pair of welds being spaced apart a sufficient distance to just accommodate a cutting instrument between them without cutting either weld area to any great extent, severing the core into two core portions by a single cutting operation between the pair of welds on each leg of said core, applying coil means to at least one of said core portions, and connecting the cut ends of said core portions together to reform substantially a closed magnetic path.
